PUMP FOR INJECTION ENGINES

René Wisner, Paris, France, assignor to Société
Anonyme André Citroën, Paris, FranceApplication November 29, 1935, Serial No. 52,221
In France December 3, 1934

3 Claims. (Cl. 103—41)

This invention relates to improvements in pumps for injecting liquid fuel into internal combustion engines of the type in which the quantity of fuel injected into each cylinder of the engine for one stroke of the corresponding piston of the feed pump is controlled by a pull member. Ordinarily the pull member whether operated manually or automatically to control the output of the pump is associated with a fixed stop against which the pull member is constantly urged in the direction to adjust the pump for increased output.

If the fixed stop is positioned to limit the movement of the pull member to the position of maximum output of the pump for normal operation of the engine at full power, difficulty is frequently experienced in starting the engine.

The object of the present invention is to provide a regulating device by which the stop member may be manually displaced beyond its position of normal maximum output of the pump so as to afford a rich fuel mixture suitable for quickly starting the engine.

In the accompanying drawings wherein an approved embodiment of the invention is illustrated:—

Figure 1 is an elevation of a pump partly in section and showing the application of the invention thereto, the regulating device occupying its normal position in which the maximum quantity of fuel necessary for normal operation of the engine at all working speeds is supplied.

Fig. 2 is a view similar to Fig. 1 showing the regulating device adjusted to increase the output of the pump to facilitate starting of the engine.

Fig. 3 is a section on the line 3—3 of Fig. 1.

Referring to the drawings in detail, the numeral 21 indicates one of the cylinders of the pump designated generally at 2, the output of which is controlled by a pull member 3 in the form of a rack connected with the accelerating pedal of the engine or a regulator which latter is not shown but is well known in the art. A piston 22 is mounted in each cylinder 21 and is adapted during reciprocation to cover and uncover the inlet ports 24 in the cylinder 21. The piston 22 is provided with a recess having an inclined wall 23 terminating in an axial passage 26 adapted to establish communication between one of the inlet ports 24 and the pressure chamber 25 of the pump cylinder. The teeth of the pull member 3 mesh with a toothed member 27 connected with the piston 22 whereby the latter is turned about its longitudinal axis within the

cylinder 21 during longitudinal movement of the pull member 3 and thereby varies the angular position of the inclined wall 23 to one of the inlet ports 24.

The pull member 3 is normally urged to the left by a spring, not shown, and ordinarily a fixed stop is provided for limiting the movement of the member 3 and thereby limiting the extent of turning movement of the piston 22 to determine the maximum output of the pump for normal running conditions of the engine.

According to the present invention, the usual fixed stop is dispensed with and a movable stop member 7 is positioned in the guide 1 for the pull member 3. The stop member 7 is provided with a threaded stem 6 slidably mounted in a support 4 rigidly connected with the guide 1. A spring 5 arranged about the stem 6 is confined between the support 4 and the stop member 7 and normally urges the latter to the right in opposition to the action of the spring, not shown, acting upon the pull member 3. The normal position of the stop member 7 is determined by a stop nut 8 fitted on the threaded end of the stem 6 and engageable with the terminal of the support 4, a lock nut 9 being provided to secure the stop nut in adjusted position.

The extreme end of the stem 6 is provided with a pin 10 engaging in a slot 11 of a lever 12 pivotally mounted at 13 on an arm 14 of the support 4. The end 15 of the lever 12 is adapted to be connected by a suitable operating device, not shown, located conveniently near the operator of the engine, the operating device being capable of retaining the lever 12 in several different positions of adjustment.

As shown in Fig. 1, the stop member 7 is moved to the right under the influence of the spring 5 until the stop nut 8 rests against the support 4 and the movement of the pull member 3 is thus limited for the adjustment of the pistons 22 for the normal operation of the engine. With this adjustment the effective stroke of the piston is designated A in Fig. 1. When it is desired to supply a rich fuel mixture for the purpose of starting the engine, the lever 12 is moved to the position shown in Fig. 2 and the stop member 7 is displaced to the left thereby permitting the pull member 3 to follow the stop member and adjust the pistons 22 to the position to increase the effective stroke as indicated at B in Fig. 2.

What I claim is:

1. In a regulating device for a pump for injecting liquid fuel in internal combustion engines in which a sliding pull member is constantly

urged in the direction to increase the pump output, the combination of a support rigid with the pump and receiving the free end of said pull member, a member engaged by and forming a stop for said pull member slidably mounted in the said support, a spring constantly displacing the stop member towards the free end of the pull member, a stopping device for limiting the action of the spring and means for momentarily displacing the stop member against the action of the spring.

2. In a regulating device for a pump for injecting liquid fuel in internal combustion engines in which a sliding pull member is constantly urged in the direction to increase the output of the pump, a support for the free end of said pull member, a stop member slidably mounted in the said support, a spring constantly urging the stop member towards the free end of the pull member, stop members for limiting the ac-

tion of the spring, and a lever for momentarily displacing the stop member against the action of the spring.

3. In a regulating device for a pump for injecting liquid fuel in internal combustion engines in which a sliding pull member is constantly urged in the direction to increase the pump output, the combination of a tubular support rigid with the pump and receiving the free end of the pull member, a stop member slidably mounted in the said support, a threaded rod rigid with the stop member, nuts mounted on the said threaded rod, a spring surrounding the said threaded rod and constantly urging the stop member towards the free end of the pull member, said nuts engaging said support and limiting the action of the said spring, and means for momentarily displacing the stop member against the action of the spring.

RENE WISNER. 20
